UNITED STATES PATENT OFFICE

104,181

DESIGN FOR A WHEELED TOY CHASSIS

William Borios, Buffalo, N. Y., assignor to Master Metal Products, Inc., Buffalo, N. Y., a corporation of New York

Application February 5, 1937, Serial No. 67,474

Term of patent 7 years

To all whom it may concern:

Be it known that I, William Borios, a citizen of the United States, residing at Buffalo, in the county of Erie and State of New York, have invented a new, original, and ornamental Design for Wheeled Toy Chassis, of which the following is a specification, reference being had to the accompanying drawing forming a part thereof.

Figure 1 is a perspective view of the wheeled toy chassis looking generally from the front end thereof. Figure 2 is a similar view looking generally from the rear end thereof.

I claim:

The ornamental design for a wheeled toy chassis, substantially as shown.

WILLIAM BORIOS.
